(57) **ABSTRACT**

Systems and methods for collecting samples from a wellbore include a gauge cutter. The gauge cutter includes a body including a central recess in a downhole end of the body extending toward an uphole portion of the body, one or more large openings in the uphole portion of the body extending from an exterior of the body into the central recess, and a cutter blade disposed at the downhole end of the body. The gauge cutter further includes a fluid collection chamber disposed within the central recess and adjacent an interior surface of the body, a wiper blade disposed around an exterior of the body; and a plurality of passageways down-hole and adjacent the wiper blade configured to allow fluid to pass from the exterior of the body into the fluid collection chamber.

20 Claims, 7 Drawing Sheets

COLLECTING SAMPLES FROM
WELLBORES

TECHNICAL FIELD

The present disclosure relates to a wellbore tool for gauging a wellbore and collecting samples in the wellbore.

BACKGROUND

Gauge cutters are commonly used in the petroleum industry for ensuring accessibility of tubing/casing/liner prior to running any other sub-surface tools inside the well. A gauge cutter is a tool with a round, open-ended bottom which is milled to an accurate size. Large openings above the bottom of the tool allow for fluid bypass while running in the hole. Often a gauge cutter will be the first tool run on a slickline operation. A gauge cutter can also be used to remove light paraffin that may have built up in the casing and drift runs also. In the case of a restriction caused by scale, debris, or paraffin, the nature of the debris can be identified such that a treatment solution can be defined and implemented. To identify the debris a sample of the debris cut from the internal diameter of the wellbore by the gauge cutter can be retrieved by an additional run of a debris catcher tool (e.g., a sand bailer tool) for analysis.

SUMMARY

This disclosure describes systems and methods for collecting samples from a wellbore while running a gauge cutter through the wellbore. In some wells (e.g., gas wells), liquid condensation can build up on the interior walls of the wellbore/production tubing. As the gas flow decreases, for example due to production of gas from the well, the gas no longer has enough energy to lift heavier liquids (e.g., water and longer chain molecules such as heptanes (C7) and larger molecules) to the surface. The mist-like drops of heavier fluids can coalesce together and form droplets on the inner diameter of tubing and/or accumulate at the bottom of the well. The condensation of heavier hydrocarbons and water on the inner wall of the wellbore can pose a problem for depleting gas wells. Often, there is no quantification of the extent and nature of condensation in correlation with depth because the condensate is not preserved in its original condition by the time logging tools are run. Often the condensate is disturbed (e.g., by a conventional gauge cutter) before appropriate logging tools for sampling or analysis are run in the wellbore. The systems and methods of this disclosure provide a way to form a clear path through the wellbore while collecting samples of the condensate during the first run of a tool in the wellbore. The systems and methods of this disclosure also provide a way of sampling solid debris from the wellbore as the tool is pulled out of the wellbore.

In one aspect, a gauge cutter includes a body including a central recess in a downhole end of the body extending toward an uphole portion of the body; one or more large openings in the uphole portion of the body extending from an exterior of the body into the central recess; a cutter blade disposed at the downhole end of the body; a fluid collection chamber disposed within the central recess and adjacent an interior surface of the body; a wiper blade disposed around an exterior of the body; and a plurality of passageways downhole and adjacent the wiper blade configured to allow fluid to pass from the exterior of the body into the fluid collection chamber.

2

In one aspect, a method of collecting samples from a wellbore includes moving a gauge cutter in a downhole direction in the wellbore; wiping, by a wiper blade of the gauge cutter, condensate from interior walls of the wellbore; collecting samples of the condensate in a condensate collection chamber of the gauge cutter; moving the gauge cutter in an uphole direction in the wellbore; and collecting samples of solid debris from the wellbore in a solids collection chamber of the gauge cutter.

10 Embodiments of these aspects can include one or more of the following features.

In some embodiments, these aspects further include a solid debris sample collector disposed within the central recess.

15 In some embodiments, these aspects further include a removable core with an upper seal and a lower seal.

In some embodiments, an annular space between the removable core, the upper seal, the lower seal, and the interior surface of the body define the fluid collection chamber.

20 In some embodiments, these aspects further include a liquid collecting sponge. In some cases, the liquid collecting sponge includes an oil wettable sponge.

In some embodiments, these aspects further include a 25 sensor module comprising an annular housing and positioned adjacent the fluid collection chamber. In some cases, the sensor module includes at least one of a fluid detection sensor, a water-cut sensor, a depth sensor, and a pressure sensor. In some cases, the sensor module is configured to allow collection of fluid in the fluid collection chamber based on a sensed pressure or depth in a wellbore.

In some embodiments, the wiper includes an elastomeric material.

30 In some embodiments, the plurality of passageways includes capillary tubes.

In some embodiments, these aspects include removing the solid collection chamber and the condensation collection chamber from the gauge cutter to access the collected samples.

40 In some embodiments, these aspects further include measuring at least one of a pressure, a depth, and a presence of a liquid in the wellbore by a sensing module of the gauge cutter.

In some cases, collecting samples of the condensate occurs after the sensing module measures a pre-defined pressure or depth in the wellbore.

45 In some embodiments, while moving the gauge cutter in the downhole direction, solid debris passes through the gauge cutter without being collected.

50 In some embodiments, wiping includes condensate pooling on a downhole side of the wiper blade.

In some embodiments, collecting samples of the condensate includes condensate flowing through a plurality of passageways of the gauge cutter from an exterior of the 55 gauge cutter into the condensate collection chamber.

In some cases, these aspects further include retaining condensate in a liquid catching sponge disposed within the condensate collection chamber.

In some embodiments, these aspects further include collecting a sample of liquid located at a bottom of the wellbore.

Certain implementations can have particular advantages. The systems and methods of this disclosure combine sampling liquid and solid debris from a wellbore along with a 60 gauge cutter run. Since the gauge cutter is the first tool to be run in the wellbore, the liquid sample catcher can collect samples of the liquid from the well in an undisturbed

condition. Combining the sample collection with the gauge cutter tool avoids using a separate logging tool on a subsequent run to collect debris or liquid samples. Samples collected using the systems and methods of this disclosure can provide insight on the behavior of a particular reservoir or well. For example, the samples can provide insight on changes in produced gas composition, and/or indications of scaling or corrosion that can be expected in the well.

The details of one or more embodiments of these systems and methods are set forth in the accompanying drawings and the description below. Other features, objects, and advantages of these systems and methods will be apparent from the description and drawings, and from the claims.

DESCRIPTION OF DRAWINGS

FIGS. 1A-1C show side, front, and cross section views of a gauge cutter configured to collect samples from a wellbore.

FIGS. 2A-2C show front, cross section, and detail views of a removable core for a gauge cutter to collect samples from a wellbore.

FIGS. 3A-3B show a gauge cutter to collect samples from a wellbore including a liquid collection sponge and a sensor module.

FIGS. 4A-4C shows a gauge cutter with liquid and solid collection chambers defined by the internal geometry of the gauge cutter.

FIG. 5 is a flow chart of a method for collecting samples from a wellbore.

FIG. 6 illustrates condensate collections from a wellbore during a run of a gauge cutter.

FIGS. 7A-7B illustrate collection of solid samples from a wellbore during run-in-hole and pull-out-of-hole.

DETAILED DESCRIPTION

This specification describes systems and methods for collecting samples from a wellbore while running a gauge cutter through the wellbore. In some wells (e.g., gas wells), liquid condensation can build up on the interior walls of the wellbore or production tubing. As the gas flow decreases, for example due to reduced reservoir pressure from production of gas from the well, the gas no longer has enough energy to lift heavier liquids (e.g., water and longer chain molecules such as heptanes (C7) and larger molecules) to the surface. The mist-like drops of heavier fluids can coalesce together and form droplets on the inner wall of the wellbore or tubing and/or accumulate at the bottom of the well. Often the condensate is disturbed before appropriate logging tools for sampling or analysis are run in the wellbore. The systems and methods of this disclosure provide a way to collect samples of the condensate during the first run of a tool in the wellbore. The systems and methods of this disclosure also provide a way of sampling solid debris from the wellbore as the tool is pulled out of the wellbore.

Maturing reservoir wells over time can experience a reduction in tubing/casing internal diameter due to scale production and accumulation. A gauge cutter can be run through the wellbore to allow accessibility of tubing, casing, and liner for other tools to be run in the wellbore. Gauge cutters can come in different sizes. The size of gauge cutter chosen for a particular application can be dependent on, for example, the inner diameter of the wellbore, the diameter of subsequent tools to be used, or other factors. A gauge cutter can be used to tag the plug back total depth (PBTD), which is the depth of the well to the cement plug placed at the bottom of the producing zone (e.g., the accessible depth in

the wellbore). A gauge cutter can also be used to clean a wellbore from soft paraffin and soft scale that has developed over time.

FIGS. 1A-1C show side, front, and section views of a gauge cutter 100 configured to collect samples from a wellbore. The gauge cutter 100 includes a cylindrical body 102 with an uphole end 104 and a downhole end 106. The uphole end 104 can include a standard wireline connection 108 and a fishing neck 110 to connect to a slickline. The downhole end 106 includes a cutter blade 112. The cutter blade 112 is configured to scrape cut, scour or dislodge debris from the interior walls of the wellbore. The cylindrical body 102 can be a single piece. A central recess 114 is defined within the cylindrical body 102 extending from the downhole end 106 toward the uphole end 104. The central recess 114 defines an interior wall 116 of the cylindrical body 102. One or more large openings 118 are defined in the cylindrical body 102 allowing access to the central recess 114 in the uphole portion of the central recess 114.

A wiper blade 120 is disposed around the exterior of the cylindrical body downhole from the large openings 118. The wiper blade 120 can include an elastomeric material or a plastic material. For example, the wiper blade can include polyurethane, silicone, fluoroelastomers, nitrile, polychloroprene, and ethylene propylene diene monomer (EPDM). The wiper blade 120 is configured to contact the interior walls of the wellbore and wipe condensate from the wellbore. The wiper blade can have an outer diameter larger than an outer diameter of the cylindrical body. The wiper blade can be flexible and configured to bend to allow the gauge cutter to pass through the wellbore. Condensate wiped from the wellbore can coalesce and pool on the downhole side of the wiper blade 120.

In some implementations, wiper blade 120 can include overlapping fingers or flaps. In these implementations, the wiper blade 120 can include a thin, flexible plastic, for example, polypropylene.

The cylindrical body 102 includes a plurality of passageways 126 extending from the exterior of the body 102 into the central recess 114. The plurality of passageways 126 is downhole from the wiper blade 120 and positioned to collect condensate wiped from the wellbore. The plurality of passageways 126 can be evenly spaced around the circumference of the cylindrical body 102. Each passageway 126 can have a small diameter (e.g., 0.05 mm, 1 mm, 2 mm). In some implementations, the plurality of passageways 126 can include passageways with different diameters. For example, a portion of the plurality of passageways 126 can have a diameter of 0.05 mm and a second portion of the plurality of passageways 126 can have a diameter of 2 mm. The plurality of passageways 126 can be capillary tubes configured to draw liquid from the exterior of the gauge cutter 100 to the central recess 114 using capillary forces between the liquid and the interior of the plurality of passageways 126. In some implementations, the liquid flows through the plurality of passageways 126 based on a pressure differential between a pressure exerted on condensate accumulated on the downhole side of the wiper blade 120 and the pressure inside the condensate collection chamber 128.

An annular condensate collection chamber 128 is disposed within the central recess 114 adjacent the interior wall 116 of the cylindrical body 102. The condensate collection chamber 128 is configured to collect condensate from the plurality of passageways 126. The condensate collection chamber 128 can be removable from the cylindrical body 102.

In some implementations, the condensate collection chamber 128 can be defined by a removable core 130 disposed within the central recess 114 of the gauge cutter 100. The removable core 130 can be made from plastic, metal, polymer, elastomer or combinations thereof. The removable core 130 can be attached to the cylindrical body 102 by a mechanical fastener 132, for example, a snap fit connection, magnetic connection, bolted connection, or tongue and groove connection. The removable core 130 includes an upper seal 134 and a lower seal 136. When inserted into the central recess 114, the removable core 130 defines an annular space 138 between the wall of the removable core 130 and the interior walls 116 of the cylindrical body 102. The annular space 138 is bounded in the uphole direction by the upper seal 134 and in the downhole direction by the lower seal 136. The annular space 138 can define the condensate collection chamber 128.

Uphole of the upper seal 134, a second annular space 140 is defined between the removable core 130 and the interior walls 116 of the cylindrical body 102. The uphole portion 142 of the removable core 130 includes slots 144 that are fluid permeable. In some implementations, the uphole portion 142 can include holes and/or a mesh instead of or in addition to slots 144. The second annular space 140 defines a solid debris collection chamber 146. When the gauge cutter 100 is pulled out of the wellbore, the solid collection chamber 146 can collect solid debris suspended in the fluid within the wellbore.

FIGS. 2A-2C show front, cross-section, and detail views of an example removable core 130. The removable core 130 includes a tubular core body 150 with an open central passageway 152 extending the entire length of the tubular core body 150. A downhole portion 154 of the tubular core body 150 can have a wall thickness 156 larger than a wall thickness 158 of the uphole portion 142. The upper seal 134 can rest on the shoulder 160 created by the difference in the wall thicknesses 156 and 158. The distance 162 between the lower seal 136 and the shoulder 160 defines the distance between the lower seal 136 and the upper seal 134. The distance 162 also defines the height of the condensate collection chamber 128. The surfaces of the downhole portion 154 of the tubular core body 150 are solid (e.g., no holes penetrate the walls of the downhole portion 154) and not permeable to fluids. The lower seal 136 can be integrated with the tubular core body 150. In some implementations, the lower seal 136 can be a separate piece fitted to the tubular core body 150. The upper seal 134 can be a separate piece from the tubular core body 150. The upper seal 134 and lower seal 136 can include a groove 164 where a gasket 135, 137 (e.g., an O-ring) can be positioned to form a fluid tight seal with the interior walls 116 of the gauge cutter 100.

FIG. 3A illustrates an example liquid catching sponge 180 that can be included in some implementations. The liquid catching sponge 180 can be included in the condensate collection chamber 128. The sponge 180 can assist the retention and collection of condensate samples in the condensate collection chamber 128. In some implementations, a liquid catching sponge 180 can be made wettable to certain fluids. For example, the liquid catching sponge 180 can be oil wettable, or the sponge 180 can be water wettable. The type of sponge fitted into the condensate collection chamber 128 can be bespoke to a condensate expected to be or known to be within the wellbore. In some implementations, the liquid catching sponge 180 can include multiple types of wettable sponges. In these implementations, the liquid catching sponge 180 can be configured within the condensate collection chamber 128 such that the volume of different

fluids collected can be estimated from the retrieved condensate samples. In some implementations, the bottom most part 182 of the liquid catching sponge 180 can collect liquid accumulated at the bottom of the well.

FIG. 3B illustrates an example sensor module 190 that can be included in some implementations. The sensor module 190 can include, for example, a fluid detection sensor, a water-cut sensor, a depth sensor, a pressure sensor, or a combination of sensors. The sensor module 190 can provide additional information on when and where condensate samples are collected during a running-in-hole (RIH) operation. The sensor module 190 can be housed in an annular housing 192 and can be disposed within the second annular space 140 uphole of the upper seal 134 surrounding the uphole portion 142 of the removable core 130.

The sensor module 190 can include a battery to provide power to the sensors of the sensor module. The sensor module 190 can also include a memory to store data and measurements detected by the sensors. The memory can be accessed, and data retrieved from the memory after the gauge cutter 100 is removed from the wellbore.

In some implementations, the sensor module 190 can be configured to start collection of condensate samples in the condensate collection chamber 128 at a pre-defined pressure or depth within the wellbore. In some implementations, a fluid detection sensor can be configured to detect concentrations of a particular fluid or multiple fluids (e.g., hydrogen sulfide, carbon dioxide, heptane).

FIG. 4A illustrates a cross-section view of an example gauge cutter 200 including a sensor module 190 and a liquid catching sponge 180. The liquid catching sponge 180 is included within the condensate collection chamber 128. The sensor module 190 is included within the second annular space 140 uphole of the upper seal 134. The solid debris collection chamber 146 is uphole of the sensor module 190.

FIGS. 4B-4C show example configurations of gauge cutters 210, 212. Gauge cutters can be configured to match desired volumes for condensate collection and solid debris collection according to the specific application or wellbore 40 without changing the overall design of the gauge cutter. FIG. 4B shows gauge cutter 210 which includes a longer condensate collection chamber 214 and a smaller solid debris collection chamber 216 as compared with gauge cutters 100 or 200. FIG. 4C illustrates a gauge cutter 212 that includes 45 a larger solid debris collection chamber 220 and a smaller condensate collection chamber 222. In some implementations, the total length 224 of the gauge cutter 210 or 212 can remain the same while the lengths of the sample collection chambers are altered. In some implementations, the total length 224 of the gauge cutter and the lengths of the condensate and solid debris sample collection chambers can be customized without changing the tool functionality.

FIG. 5 is a flow chart of an example method 250 for collecting samples from a wellbore. The method 250 includes using a gauge cutter including a wiper blade disposed around the exterior circumference of the gauge cutter and a sample collection chamber interior to the gauge cutter (e.g., gauge cutter 100). The gauge cutter is moved in a downhole direction (252). The gauge cutter can be the first 55 tool run in a wellbore to cut a clear path through debris (e.g., paraffin or scaling) that would otherwise prevent subsequent tools from being run through the wellbore. The sample collection chamber of the gauge cutter can include a condensate collection chamber and a solids collection chamber.

Condensate on interior walls of the wellbore is wiped by the wiper blade of the gauge cutter (254). Condensate (e.g., water and hydrocarbons) can form on the interior walls of

the borehole. The condensate can be collected in a condensate collection chamber of the gauge cutter (256). In some implementations, the condensate collection can begin at a specified depth or pressure within the wellbore. In some implementations, a sensor module records locations and other properties (e.g., pressure) within the wellbore where condensate is collected. In some implementations, a sample of liquid from the bottom of the wellbore is collected in the condensate collection chamber. In some cases, the samples of condensate are retained by a liquid catching sponge disposed within the condensate collection chamber.

FIG. 6 shows a cross section of a wellbore 300 and a gauge cutter 302 illustrating wiping of condensate 304 from the wellbore 300 while the gauge cutter 302 is moved in a downhole direction 306 (e.g., RIH). A wiper blade 308 of the gauge cutter 302 contacts the interior walls 310 of the wellbore 300. As the gauge cutter 302 moves downhole, condensate 304 that has formed on the interior walls 310 of the wellbore 300 accumulates in a pool 312 on the downhole side of the wiper blade 308. The pool 312 of condensate 304 can grow large enough to contact openings of passageways 314 that extend from the exterior 316 of the gauge cutter 302 into a condensate collection chamber 318 disposed adjacent the interior surface 320 of the gauge cutter 302. The passageways 314 can be capillary holes that draw the condensate 304 from the pool 312 of condensate into the condensate collection chamber 318. Within the condensate collection chamber 318, the collected condensate 322 pools in the bottom of the chamber. In some implementations, the condensate collection chamber 318 is formed between the surface of a removable core 324 and the interior walls 320 of the gauge cutter 302. A lower seal 326 and an upper seal 328 prevent leakage of the collected condensate 322 out of the condensate collection chamber 318. The lower seal 326 and upper seal 328 also prevent contamination of the collected condensate 322 by other fluids present in the wellbore. Since the gauge cutter 302 is the first tool run in the wellbore 300 during an intervention, the probability of obtaining a sample of condensate 304 is higher than for subsequent intervention tool runs because the well and condensate have not been disturbed.

In some implementations, the openings of the passageways 314 can become blocked by solid debris from the interior walls 310 of the wellbore 300. Multiple passageways can be provided in the body of the gauge cutter 302 to increase the likelihood of sampling condensate 304 in the wellbore 300. After retrieval of the gauge cutter 302 from the wellbore 300, debris blocking the passageways 314 can be removed and analyzed to provide additional insight into the behavior of the well or reservoir.

FIG. 7A illustrates a cross section of a gauge cutter 350 removing solid debris 352 from the interior walls 354 of a wellbore 356. Solid debris 352 (e.g., scale and paraffin) can accumulate on the interior walls 354 of the wellbore 356 decreasing the internal diameter 358 of the wellbore 356. A function of the gauge cutter 350 is to define a known passage diameter within the wellbore 356. In the event of the formation of scale 357, the gauge cutter 350 can be forced through the scale 357 cutting the known passage diameter (e.g., the external diameter 360 of the gauge cutter). As the gauge cutter 350 is moved in a downhole direction 362 (e.g., RIH), the cutter blade 364 scrapes, cuts, and/or dislodges the solid debris 352 forming a clear path through the wellbore 356 of the diameter 360 of the gauge cutter 350. The solid debris 352 that is removed from the wellbore 356 and fluid 365 within the wellbore 356 can move in an uphole direction relative to the gauge cutter 350. The solid debris 352 and

fluid can pass through the open aperture 366 in the downhole end 368 of the removable core 370 and central recess 372 of the gauge cutter 350. The solid debris 352 and fluid can exit the central recess 372 through the large openings 374 in the uphole portion 376 of the gauge cutter 350 bypassing the solid debris collection chamber 378. In this scenario the wiper blade 379 installed around the external diameter 360 of the gauge cutter 350 can fold backwards (e.g., in an uphole direction) providing a low resistance to pushing the gauge cutter 350 through the scale deposits on the interior walls 354 of the wellbore 356 during RIH operations. The gauge cutter 350 can simultaneously collect condensate samples as discussed with reference to FIG. 6.

Turning back to method 250 in FIG. 5, the gauge cutter 15 can be moved in an uphole direction, for example, while being pulled out of the hole (POOH) (258). The gauge cutter can collect samples of solid debris in a solids collection chamber of the gauge cutter (260). For example, in gauge cutter 100, solid debris can be collected in the solids collection chamber 146 formed by the annular space 140 between the removable core 130 and the interior walls 116 of the gauge cutter. The solid debris collection chamber collects a small portion of the solid debris within the wellbore. For example, the solid collection chamber can 20 collect 50 grams to 1000 grams of solid debris. The amount of solid debris collected depends on the volume of the solid debris collection chamber. For example, the solid debris collection chamber can have a volume of 0.3 L to 1 L. Other solid debris collection chambers can have other volumes (e.g., a volume of 0.1 L to 1.5 L).

35 Samples collected in the wellbore can be removed from the gauge cutter by removing the solid debris collection chamber and the condensate collection chamber from the gauge cutter (262). In some implementations, the collected samples are packaged for transportation to a laboratory facility where further analysis and measurements are performed. In some implementations, analysis and measurements of the collected samples can be performed at the well site.

40 Example analysis that can be performed on the collected samples include separating liquid hydrocarbons from water mechanically (e.g., using a centrifuge) or chemically (e.g., using a demulsifier). The fraction of different long-chain alkanes like heptanes, octanes, nonanes within the liquid 45 hydrocarbon phase can be characterized using a gas chromatograph. A detailed breakdown of the composition of liquid in the well bore can help in mitigating future flow assurance issues. For example, an operator can decide between several actions depending on the known composition 50 of liquid in the wellbore. Example actions include applying a different choke setting at the surface to produce less liquid, deciding to inject scale inhibitors, and boosting reservoir pressure by water injection.

FIG. 7B illustrates the collection of solid debris 352 when 55 the gauge cutter 350 is pulled out of hole (POOH) (e.g., moving the gauge cutter 350 in an uphole direction 380). Fluid 365 and entrained and/or suspended solid debris 352 enter the central recess 372 of the gauge cutter 350 through the large openings 374 and exit through the open aperture 366 in the downhole end 368. A portion of the fluid 382 flows into the second annular space 384 between the interior walls 386 of the gauge cutter 350 and the removable core 370. The portion of fluid 382 can flow into the second 60 annular space 384, through the slots 388 in the removable core 370, and exit the central recess 372 through the open aperture 366 in the downhole end 368 of the gauge cutter 350. Solid debris 352 entrained in the portion of fluid 382

that is larger than the width of the slots 388 in the removable core 370 can be retained in the annular space 384 and settle into the solid debris collection chamber 378. The solid debris collection chamber 378 can collect solid debris 352 until the solid debris collection chamber is full. After filling the solid debris collection chamber 378, the fluid 365 within the wellbore can continue to flow through the open aperture 366 in the removable core 370. Entrained solid debris 352 can follow the fluid path 365 and exit the gauge cutter 350 through the open aperture 366 in the downhole end 368.

A number of embodiments of these systems and methods have been described. Nevertheless, it will be understood that various modifications may be made without departing from the spirit and scope of this disclosure. Accordingly, other embodiments are within the scope of the following claims.

What is claimed is:

1. A gauge cutter comprising:
a body comprising:
a central recess in a downhole end of the body extending toward an uphole portion of the body;
one or more openings in the uphole portion of the body extending from an exterior of the body into the central recess;
a cutter blade disposed at the downhole end of the body;
a fluid collection chamber disposed within the central recess and adjacent an interior surface of the body;
a wiper blade disposed around an exterior of the body; and
a plurality of passageways downhole and adjacent the wiper blade configured to allow fluid to pass from the exterior of the body into the fluid collection chamber.
2. The gauge cutter of claim 1, further comprising a solid debris sample collector disposed within the central recess.
3. The gauge cutter of claim 1, further comprising a removable core with an upper seal and a lower seal.
4. The gauge cutter of claim 3, wherein an annular space between the removable core, the upper seal, the lower seal, and the interior surface of the body define the fluid collection chamber.
5. The gauge cutter of claim 1, further comprising a sensor module comprising an annular housing and positioned adjacent the fluid collection chamber.
6. The gauge cutter of claim 5, wherein the sensor module comprises at least one of a fluid detection sensor, a water-cut sensor, a depth sensor, and a pressure sensor.
7. The gauge cutter of claim 5, wherein the sensor module is configured to allow collection of fluid in the fluid collection chamber based on a sensed pressure or depth in a wellbore.
8. The gauge cutter of claim 1, wherein the wiper comprises an elastomeric material.
9. The gauge cutter of claim 1, wherein the plurality of passageways comprises capillary tubes.
10. A gauge cutter comprising:
a body comprising:

a central recess in a downhole end of the body extending toward an uphole portion of the body;
one or more openings in the uphole portion of the body extending from an exterior of the body into the central recess;
a cutter blade disposed at the downhole end of the body;
a fluid collection chamber disposed within the central recess and adjacent an interior surface of the body;
a wiper blade disposed around an exterior of the body;
a plurality of passageways downhole and adjacent the wiper blade configured to allow fluid to pass from the exterior of the body into the fluid collection chamber; and
a liquid collecting sponge.

11. The gauge cutter of claim 10, wherein the liquid collecting sponge comprises an oil wettable sponge.

12. A method of collecting samples from a wellbore comprising:
moving a gauge cutter in a downhole direction in the wellbore;
wiping, by a wiper blade of the gauge cutter, condensate from interior walls of the wellbore;
collecting samples of the condensate in a condensate collection chamber of the gauge cutter;
moving the gauge cutter in an uphole direction in the wellbore; and
collecting samples of solid debris from the wellbore in a solids collection chamber of the gauge cutter.

13. The method of claim 12, further comprising removing the solid collection chamber and the condensation collection chamber from the gauge cutter to access the collected samples.

14. The method of claim 12, further comprising measuring at least one of a pressure, a depth, and a presence of a liquid in the wellbore by a sensing module of the gauge cutter.

15. The method of claim 14, wherein collecting samples of the condensate occurs after the sensing module measures a pre-defined pressure or depth in the wellbore.

16. The method of claim 12, wherein while moving the gauge cutter in the downhole direction, solid debris passes through the gauge cutter without being collected.

17. The method of claim 12, wherein wiping comprises condensate pooling on a downhole side of the wiper blade.

18. The method of claim 12, wherein collecting samples of the condensate comprises condensate flowing through a plurality of passageways of the gauge cutter from an exterior of the gauge cutter into the condensate collection chamber.

19. The method of claim 18, further comprising retaining condensate in a liquid catching sponge disposed within the condensate collection chamber.

20. The method of claim 12, further comprising collecting a sample of liquid located at a bottom of the wellbore.
